(57) **CLAIM**

I claim the ornamental design for an elastic cable holder, as shown and described.

DESCRIPTION

FIG. 1 is a perspective view of an elastic cable holder, showing a first embodiment of my new design in a bent position;

FIG. 2 is a perspective view thereof, illustrated in a flat position;

FIG. 3 is a front elevational view of FIG. 2, the rear elevational view being a mirror image thereof;

FIG. 4 is a left-side elevational view of FIG. 2, the right-side elevational view being a mirror image thereof;

FIG. 5 is a top plan view of FIG. 2; and,

FIG. 6 is a bottom plan view of FIG. 2.

The broken lines showing cords in FIGS. 1 and 2 depict environmental subject matter and form no part of the claimed design.
